JOSEF KIRNER, OF STUTTGART, GERMANY, ASSIGNOR TO NORMA COMPAGNIE GESELLSCHAFT MIT BESCHRAENKTER HAFTUNG, OF CANNSTATT-STUTTGART, GERMANY, A CORPORATION OF GERMANY.

APPARATUS FOR GRINDING THE SURFACE OF ROLLERS.

1,168,006.

Specification of Letters Patent. Patented Jan. 11, 1916.

Application filed February 5, 1914. Serial No. 816,785.

To all whom it may concern:

Be it known that I, JOSEF KIRNER, a citizen of the German Empire, and residing at Stuttgart, Germany, have invented a new and useful Improvement in Apparatus for Grinding the Surface of Rollers, of which the following is a specification.

This invention relates to a grinding machine for grinding in a simple, efficient and accurate manner the surfaces of rollers used for antifriction bearings and other purposes.

In the accompanying drawings, which show an embodiment of my invention: Figure 1 shows diagrammatically the mechanism for grinding the rollers with a bore, in front view, Fig. 2 is a side-view, Fig. 3 is a top-view, showing the grinding disk in section, and Figs. 4 and 5 are top-views of the roller and mounting therefor, showing details thereof.

Similar reference numerals indicate corresponding parts throughout the various views.

The grinding disk *a* is turned by the shaft *b* in the direction of the arrow shown. The roller *c* to be ground is carried by a suitable fixed support *d*, and sits loosely on the stationary guide pin *f*, which can be suitably placed opposite the disk *a*, so as to be in proper position, to hold the roller *c* against the grinding surface of the disk *a*. Thereby the roller *c* touches the grinding surface in a line of its convex or exterior surface. The components of the motion of the contact points coincident with this surface line bring about a grinding effect in this direction, whereas the components lying at right angles thereto bring about a turning of the roller on the pin *f* according to the arrow shown in Fig. 3. The condition for the existence of both of these effects is that the contact surface line should neither be coincident with a diameter of the grinding disk, nor lie in the middle of a chord. Depending

on the regulation between these two limiting positions, one or the other or both of these effects may be made to prevail over the other. In other words the line of contact of the work with said disk is at an angle to both the radial and chord lines of said disk which pass through said line of contact, whereby a swiping action of the disk occurs. This swiping action is neither a direct axial longitudinal pressure nor a direct tan-

gential pressure, but a compound between the two and acts not only to grind the roller longitudinally and to rotate it to bring its circumference in position but also operates to hold it on the work spindle. If now, a simple cylindrical pin be employed as a guide for the roller, in accordance with Fig. 4, then, under the influence of the rapid turning of the roller, a pendulum movement of the same around the stationary pin *f* would take place, and the roller will swing to and fro as indicated in Fig. 4, between the position shown in full lines and the position shown in dotted lines. The contact surface lines between the stone and the roller, which lines correspond to both of these positions, would then have a different distance from the pin *f*, than is the case with the position shown in Fig. 3.

According to the above invention, the roller *c* is thereby given a secure guidance, in that the pin *f* touches in two lines, which, following Fig. 3, are for example, thought generated thereby, that the forward surface of the originally cylindrical pin *f* is flattened, as shown in Fig. 3. The roller thus lies against the edges *g* and *h* and these guiding edges *g* and *h* form with the contact surface line a three-edged prism, and therewith a secure bearing for the roller. Instead of using the edges *g* and *h*, two separate rods *i* and *k*, as shown in Fig. 5, may be used. Mathematically, three points in the interior of the roller are sufficient.

It is advantageous not to place the guide pin *f* perpendicularly, but to so incline it with the remaining parts of the machine, that the rollers will lean against the guide pin by reason of their own weight. In order that the original, that is, plane form of the grinding surface is maintained, the guide pin *f* can be moved during the grinding to and fro parallel with the grinding surface.

The invention is adapted not only to the working of cylindrical surfaces, but to other desired surfaces of revolution. If it concerns the making of other than regular surfaces, the grinding plate must show a correspondingly curved form, and must be kept permanently in this form, for example, by suitable supplementary relative movements between the piece worked upon, respectively, the guide pin and disk.

Although the invention has special advantages for the making of rollers whose exterior surfaces should be exactly axially arranged with respect to the boring passing through it, its application is not limited to the making of such rollers, but in the same manner other rollers also, as for instance, rollers with pivots or pegs, could also be ground.

10 Several embodiments of my invention have been shown, and it is clear that changes may be made therein without departing from the spirit of the invention as defined in the appended claims.

15 Having thus described my invention, what I desire to secure by Letters Patent is:—

1. A roller grinding machine comprising a rotary disk having a facial grinding surface, and a work holding means adapted to hold a roller along a longitudinal line of grinding contact in engagement with said facial grinding surface, its line of contact with said disk being at an angle to both the radial and chord lines of said disk which pass through said line of contact, the face of said rotary disk having a swiping contact with said roller and being operative to simultaneously grind the surface thereof and to rotate said roller to cause the longitudinal line of grinding contact to traverse the circumference of said roller.

2. A roller grinding machine comprising a rotary disk having a facial grinding surface, and a work holder having two points of contact with the interior of the roller to be ground and adapted to hold said roller along a longitudinal line of grinding contact in engagement with said facial grinding surface, the face of said rotary disk having a swiping contact with said roller and being operative to simultaneously grind the surface thereof and to rotate said roller to

cause the longitudinal line of grinding contact to traverse the circumference of said roller.

3. A roller grinding machine comprising a rotary disk having a facial grinding surface, and a work holder including a guide spindle disposed at an angle to the radial and chord lines of said disk and adapted to loosely engage the bore of and hold a roller along a longitudinal line of grinding contact in engagement with said facial grinding surface, the face of said rotary disk having a swiping contact with said roller and being operative to simultaneously grind the surface thereof and to rotate said roller to cause the longitudinal line of grinding contact to traverse the circumference of said roller.

4. A roller grinding machine comprising a rotary disk having a facial grinding surface, and a work holder including a spindle disposed in front of said facial grinding surface at an angle to the radial and chord lines of said disk and inclined toward said surface, said spindle being adapted to loosely engage the bore of a roller to be ground and to hold such roller along a longitudinal line of grinding contact in engagement with said grinding surface, the face of said rotary disk having a swiping contact with said roller and being operative to simultaneously grind the surface thereof and to rotate said roller to cause the longitudinal line of grinding contact to traverse the circumference of said roller.

In testimony that I claim the foregoing as my invention, I have signed my name in presence of two subscribing witnesses.

JOSEF KIRNER.
